UNITED STATES PATENT OFFICE.

THOMAS P. HICKS, OF NEW YORK, N. Y.

DEVICE FOR FASTENING METAL, &c., TO STONE.

SPECIFICATION forming part of Letters Patent No. 734,326, dated July 21, 1903.

Application filed October 20, 1902. Serial No. 127,998. (No model.)

To all whom it may concern:

Be it known that I, THOMAS P. HICKS, a citizen of the United States, and a resident of the city of New York, borough of the Bronx, 5 in the county and State of New York, have invented a new and Improved Device for Fastening Metal or Woodwork to Stone, of which the following is a full, clear, and exact description.

10 My invention provides a novel socket and means whereby it may be secured in a stone or in a wall for receiving a bracket or other suitable device for attaching to the stone or wall any desired article of wood or metal.

15 The invention will be hereinafter particularly described and then defined in the claims.

Reference is to be had to the accompanying drawings, forming a part of this specification, in which similar characters of reference indicate corresponding parts in all the figures.

20 Figure 1 is a longitudinal sectional view showing the socket member in place in a stone and before being expanded. Fig. 2 is a similar view showing the socket expanded, 25 together with a plug for expanding the socket and a driving-tool for the plug; and Fig. 3 shows the expanded socket in side elevation and as an example a bracket secured therein, the view showing the stone in section.

30 The socket A to be inserted in a hole sunk in the stone, as 10, is threaded, as at a , or formed with an equivalent grooved or roughened exterior to engage the stone and prevent longitudinal displacement, and an expanding 35 member in the form of a plug B is employed to expand the socket, any suitable driving-tool 15 serving when struck with a hammer to drive the plug. The socket is slotted longitudinally, as at a' , to facilitate expansion,

40 and toward the inner end the socket is thickened, as at a^2 . The slits a' terminate short of the inner end of the socket. The increased thickness gives strength to the socket and produces a reduced diameter at said thickened portion. The plug B is of greater diameter than the socket at the thickened portion, whereby when the plug is driven by a blow on the driving-tool 15 the slotted portion of the socket is expanded to a firm engagement with the stone 10. The inner end of the socket has an inwardly-projecting flange a^3 to produce a broad surface at the end,

which forms a stop and prevents the plug from being driven through the socket and splitting the stone. Any undue driving force 55 exerted on the plug will thus tend to move the socket longitudinally, and this will be resisted by the broadened surface produced by the flange a^3 . This flange has the advantage over a closed end in that the socket may be 60 more readily cast.

The outer end of the plug B has a flange or head b , (see Fig. 2,) which guides the plug by fitting the bore of the socket and also assists in preventing the driving of the plug through 65 the inner end of the socket, since it will come to a bearing against the shoulder a^4 , formed at the thickened portion of the socket.

I have shown in Fig. 3 a bracket 20, which provides a pintle for a shutter 21; but any 70 other desired article may be fastened in the socket by a threaded connection, as at a^5 , or other fastening means, as will be readily understood.

75 By the described construction of socket I am enabled to do away with an extra sleeve to fit within the socket for receiving the expansive force of the plug. An example of such a sleeve is seen in Letters Patent No. 690,284, granted to me on December 31, 1901. 80 While the sleeve construction is necessary in certain classes of work, the present arrangement is preferable in some cases, besides being simpler and less costly.

Having thus described my invention, I 85 claim as new and desire to secure by Letters Patent—

1. A fastening device, consisting of an expandable socket having an integral portion thereof formed with a reduced diameter and 90 longitudinal slits, the said slits terminating short of the inner end of the socket, and an expanding member larger in diameter and adapted to be forced into said integral portion of the socket. 95

2. A fastening device, consisting of a socket of reduced diameter and increased thickness at a point toward the inner end, and an expansion-plug adapted to be driven in the socket and of a diameter larger than the reduced diameter of said socket, the reduced diameter of the socket producing a shoulder 100 and the said plug having a flanged head.

3. A fastening device, consisting of a socket

and an expansion-plug therefor, the socket having a reduced diameter at an integral portion thereof, producing a shoulder, and the plug having a flanged head.

5 4. A fastening device, consisting of a socket thickened and slitted longitudinally for a portion of its length and having a flange at its inner end, the said thickened portion producing a reduced diameter and an internal 10 shoulder, and an expansion-plug having a

flanged head, the longitudinal slits of the socket terminating short of the inner end.

In testimony whereof I have signed my name to this specification in the presence of two subscribing witnesses.

THOMAS P. HICKS.
